DESK LAMP OR SIMILAR ARTICLE

Jacob A. Mehr, Kirkwood, Mo., assignor to Dazor Manufacturing Corp., St. Louis, Mo., a corporation of Delaware

Filed July 19, 1963, Ser. No. 75,883

Term of patent 14 years

(Cl. D48—20)

FIG. 1.

FIG. 2.

FIG. 3.

FIG.4.

FIG.5.

FIG.6.

FIG. 1 is a top plan view of a desk lamp or similar article showing my new design;

FIG. 2 is a side elevational view thereof;

FIG. 3 is a bottom plan view thereof;

FIG. 4 is a front elevational view thereof;

FIG. 5 is a rear elevational view thereof, and

FIG. 6 is a perspective view thereof with a fragmentary drafting table shown in broken lines for illustrative purposes only.

My design for the desk lamp disclosed is characterized by the lamp base in association with the flexible arm portions and lamp hood as shown.

I claim:

The ornamental design for a desk lamp or similar article, substantially as shown and described.
